CLAIM

We claim the ornamental design for a laundry detergent holder, as shown and described.

DESCRIPTION

FIG. 1 is a side view of the laundry detergent holder.

FIG. 2 is a rear view of the claimed design.

FIG. 3 is a front view of the claimed design.

FIG. 4 is a top view of the claimed design.

FIG. 5 is a bottom view of the claimed design.

FIG. 6 is a perspective view of the claimed design; and,
FIG. 7 is a cross-sectional view of the claimed design along
line 7-7 in FIG. 4.**1 Claim, 6 Drawing Sheets****FIG. 1**

FIG. 2

FIG. 3

FIG. 4

FIG. 5

FIG. 7
